UNITED STATES PATENT OFFICE.

FRANKLIN J. BRINDLEY, OF ETNA GREEN, INDIANA.

DESIGN FOR A CROOK FOR SLEIGHS.

SPECIFICATION forming part of Design No. 28,286, dated February 15, 1898.

Application filed December 20, 1897. Serial No. 662,750. Term of patent 14 years.

To all whom it may concern:

Be it known that I, FRANKLIN J. BRINDLEY, a citizen of the United States, residing at Etna Green, in the county of Kosciusko and State 5 of Indiana, have invented certain new and useful Improvements in a Design for Metal Crooks for Sleighs, Sleds, &c., of which the following is a specification.

This invention relates to a design for metal 10 crooks for sleighs, sleds, &c., reference being had to the accompanying drawings, showing a part thereof, in which—

Figure 1 is a perspective view of a metal 15 crook embodying the features of my design. Fig. 2 is a like view of the opposite side, and Fig. 3 is a longitudinal vertical sectional view.

The leading feature of my design consists in a crook-body having its rear portion substantially rectangular in shape in cross-section and recessed upon its under side, the forward wall of the recess being inclined, the forward portion of the crook-body being curved 20 upwardly and having a longitudinal recess in the upper side, the recess being divided by two transverse walls, forming a transversely-arranged pocket, and the extreme forward 25 end of the crook terminating in a depending perforated side projection.

The rearward portion 1 of the crook is sub-

stantially rectangular in cross-section and is 30 provided with a recess 2 in its under side, the forward wall 3 of the recess being inclined rearwardly, whereby the forward wall and top wall of the recess describe an acute angle, the forward portion 4 of the crook being 35 curved upwardly from the portion 1 and is provided with a longitudinal recess 5 in its upper side, as shown, the recess being divided by two transverse walls 6, forming a transversely-arranged pocket 7. Extending 40 through the rear end of the body are orifices 8, and through the forward end of the body an orifice 9, said orifice 9 being located midway the sides of the body and walls 6, respectively. Depending from the body at one side 45 at the forward end thereof is a lug 10, having a transverse orifice 11.

What I claim is—

The design for a metal crook for sleds, sleighs, &c., substantially as herein shown 50 and described.

In testimony that I claim the foregoing as my invention I have signed my name in the presence of two subscribing witnesses.

FRANKLIN J. BRINDLEY.
